United States Patent Office

Des. 198,435
Patented June 16, 1964

198,435

SUCTION CLEANER

Carroll M. Gantz, North Canton, Ohio, assignor to The Hoover Company, North Canton, Ohio, a corporation of Ohio

Filed Mar. 8, 1963, Ser. No. 73,879

Term of patent 14 years

(Cl. D9—2)

The dominant features of my design reside in the portions of the drawing shown in full lines.

I claim:

The ornamental design for a suction cleaner, substantially as shown and described.
